UNITED STATES PATENT OFFICE

156,798

LAMP CASING OR SIMILAR ARTICLE

Philip O. Wright, Detroit, Mich., assignor to Packard Motor Car Company, Detroit, Mich., a corporation of Michigan

Application December 31, 1947, Serial No. 143,478

Term of patent 7 years

(Cl. D48—32)

To all whom it may concern:

Be it known that I, Philip O. Wright, a citizen of the United States, residing at Detroit, county of Wayne, State of Michigan, have invented a new, original, and ornamental Design for a Lamp Casing or Similar Article, of which the following is a specification, reference being had to the accompanying drawing, forming a part thereof.

Fig. 1 is a front perspective view taken from a point slightly above and at one side of a lamp casing incorporating my new design.

Figs. 2 and 3 are respectively front and side elevational views thereof.

The characteristic features of my design reside in the portions shown by means of full lines in the drawing.

I claim:

The ornamental design for a lamp casing or similar article, substantially as shown and described.

PHILIP O. WRIGHT.
